UNITED STATES PATENT OFFICE.

JEAN JOSEPHS AND DAVID THEODORE BERLIZHEIMER, OF PHILADELPHIA, PENNSYLVANIA, ASSIGNORS OF ONE-THIRD TO GUSTAVUS JOSEPHS, OF PHILADELPHIA, PENNSYLVANIA.

AUTOMATIC WINDING MACHINE.

Application filed March 2, 1921. Serial No. 449,122.

To all whom it may concern:

Be it known that we, JEAN JOSEPHS, a citizen of the United States, residing at Philadelphia, county of Philadelphia, State of Pennsylvania, and DAVID THEODORE BERLIZHEIMER, a citizen of the United States, residing at Philadelphia, county of Philadelphia, State of Pennsylvania, have invented a new and useful Automatic Winding Machine, of which the following is a specification.

In our prior Patent No. 1,298,221, dated March 25th, 1919, we have described and broadly claimed a novel construction of an automatic quill winding machine wherein a plurality of quills or cops are wound with thread drawn directly from the skeins without rendering it necessary to first wind the thread upon spools; and wherein, if in the course of winding of any particular quill the feed of the yarn should in any way be stopped, the mechanism which effects the winding operation will be automatically stopped, and when again started will continue its work without leaving marks of identification upon the quill where the stoppage occurs and without turning out imperfect quills.

Our present invention involves some of the generic principles of our prior patent aforesaid, and in its broad and generic scope comprehends a novel construction and arrangement of a winding machine which can be advantageously employed for winding quills, cops, spools or bobbins directly from the skeins on the swifts.

It further comprehends a novel construction of a reciprocatory carriage provided with a novel construction of a traveling head, novel means for actuating said carriage, novel means for intermittently feeding said head step by step during the reciprocations of the carriage and novel means for controlling the feed of the carriage and of the head.

It further comprehends a novel construction and arrangement of a quill support and its adjuncts, novel means for driving a spindle at a relatively high speed with respect to a slow reciprocating movement of a carriage, thereby eliminating the strain on the yarn or thread with consequent elimination

of the likelihood of the yarn or thread breaking during the winding operation, and novel means for effecting the revolution of the spindles and stopping their revolution in case the yarn or thread becomes broken or upon completion of the quill.

It further comprehends novel means for effecting the release of the thread carrier from its feed when it is desired to manually return the thread carrier to its starting position.

It further comprehends novel means for guiding the yarn and thread so that it does not come into direct contact with any metallic part.

It further comprehends a novel construction and arrangement of yarn severing mechanism and novel means for resetting the movable knife when the thread carrier is returned to its starting position on its carriage.

It further comprehends a novel construction and arrangement of a winding machine having sets of winding mechanisms on opposite sides of the machine, novel starting and stopping mechanism, and novel means for adjusting the machine, so that the same machine can be employed for forming quills, cops, bobbins or spools on one or both sides of the machine with yarn or thread of different qualities or characteristics.

It further comprehends a novel construction and arrangement whereby a number of winding mechanisms may be removed from the machine without interfering with the operation of the other winding mechanisms which have been left on the machine, so that one or more spindles and the co-operating winding mechanism will form a separate and distinct unit.

It further comprehends novel mechanism for adjusting the feed in accordance with the grade of yarn or thread which is employed.

It further comprehends novel means for positively arresting the forward movement of the thread carrier in case the yarn or thread should bunch up and retain the lever controlling the release of the carriage feed in its operative position.

It further comprehends a novel construction and arrangement of controlling mecha-

nism whereby the machine may be started by the actuation of a single lever.

It further comprehends a novel construction and arrangement of brake mechanism.

5 Other novel features of construction and advantage will hereinafter more clearly appear in the detailed description of the operation.

For the purpose of illustrating our invention, we have shown in the accompanying drawings a typical embodiment thereof which is at present preferred by us, since said embodiment will be found in practice to give satisfactory and reliable results; although it is to be understood that the various instrumentalities of which our invention consists can be variously arranged and organized and that our invention is not limited to the precise arrangement and organization of these instrumentalities as herein shown and described.

Figure 1 represents a top plan view of a portion of a wrapping machine, embodying our invention.

25 Figure 2 represents an end elevation of the machine.

Figure 3 represents a portion of the machine in front elevation.

30 Figure 4 represents a section on line 4—4 of Figure 6.

Figure 5 represents a section on line 5—5 of Figure 6.

35 Figure 6 represents a section substantially on line 6—6 of Figure 5, certain of the parts being shown in elevation.

Figure 7 represents, on an enlarged scale, a section on line 7—7 of Figure 8.

Figure 8 represents a section substantially on line 8—8 of Figure 1.

40 Figure 9 represents, in front elevation, a portion of the machine showing more particularly the carriage and certain of its operating mechanism.

Figure 10 represents a section on line 45 10—10 of Figure 8.

Figure 11 represents, in section, a releasing device seen in Figure 8, showing certain of the parts in a different relation from that seen in Figure 8.

50 Figure 12 represents a section similar to Figure 8 but showing the parts in the position which they assume when the carriage is stopped.

Figure 13 represents, in elevation, a detail 55 of the knife mechanism.

Figure 14 represents a front elevation of the construction seen in Figure 12.

Figure 15 represents a section on line 15—15 of Figure 14.

60 Figure 16 represents a section on line 16—16 of Figure 12.

Figure 17 represents, in perspective and in detached position, certain of the members showing more particularly the manner

in which they can be coupled together and 65 taken apart when it is desired to remove one or more of the winding mechanisms from the machine so that the carriages remaining will be operative to wind quills, cops, bobbins or spools.

70

The framework of the machine.

The frame of the machine consists of end standards 1 and a desired number of intermediate standards 2, the number of which 75 latter will vary in accordance with the length of the machine, it being understood that in accordance with our present invention the machine may have any desired length so that any desired number of quills may be 80 wound at the same time at one side or both sides of the machine. The end standards and the intermediate standards are connected together by means of the upper rods or bars 3 and 4, respectively, which at their 85 free ends are threaded and provided with the nuts 5 and 6, respectively. The rods 3 and 4 intermediate their ends are braced and maintained in spaced relationship by means of brackets 7 which are secured in 90 position by means of the bolts 8, it being understood that a split bracket is employed which is secured in clamped relationship with the rods 3 and 4, respectively, by means of the bolts 8.

9 and 10 represent superimposed longitudinally extending rods which also pass through the standards 1 and 2 of the frame. The standards at their lower ends are braced by means of the rods 11, and it will of course 100 be understood that any additional or other desired form of bracing members may be employed to give the requisite rigidity to the frame.

The driving mechanism.

The prime mover employed to drive the winding machine may be of any desired nature, but in practice it preferably consists of an electric motor 12, suitably carried by 110 a fixed portion of the frame. The motor 12 has its shaft provided with a sprocket wheel 13, around which passes a sprocket chain 14, which latter also passes around a sprocket wheel 15, which is keyed at 16, to a shaft 17, 115 which is mounted in journal brackets 18 carried by the machine frame and provided with an end thrust bearing of any desired type.

The sprocket wheel 15, see more particularly Figures 5 and 6, is provided on one 120 side with a friction face 19 against which bears a friction disc 20 which co-operates with a friction disc 21 provided with a sleeve 22 which is slidably mounted on a sleeve 23, which latter is rotatably mounted 125 on the shaft 17, suitable bushings 24 being inserted between the shaft 17 and the sleeve 23. The sleeve 22 of the friction disc 21

105

95

105

110

115

120

125

is keyed to the sleeve 23 by means of a key 25, so that the sleeve of the friction disc is adapted to have relative longitudinal movement with respect to the sleeve 23 but rotates in unison with it. The outer end of the sleeve 22 forms a clutch collar 26 adapted to receive the clutch pins 27 of a yoke 28, which latter is pivotally mounted at its lower end, as at 29, to a fixed portion of the machine frame. The sleeve 22 is recessed, as at 30, in proximity to its outer end in order to receive a spring 31, one end of which bears against the inner shoulder of the recess while the opposite end bears against a pinion 32 which is keyed to the sleeve 23. The yoke 28 carries at its upper end, see more particularly Figure 6, a casting 33, in which is mounted a plunger 34 against the upper portion of which bears one end of a spring 35 the lower end of which bears against the lower wall of the casing so that the spring 35 has a tendency to maintain the plunger 34 in its raised position.

The plunger 34 at its lower end carries a U-shaped locking member 36, the sides of which overhang the upper portion of the yoke 28. The machine frame carries a bracket 37 which is mounted, as illustrated, on one of the rods 4, see Figures 1 and 2, and this bracket is apertured, as at 38, in order to permit the upper arm of the yoke 28 to extend therethrough.

The bracket 37 is provided with a shoulder 39 with which the locking member 36 cooperates to retain the friction disc 21 in its inoperative position, it being apparent that when the plunger 34 is moved downwardly the spring 31, see more particularly Figures 5 and 6, will cause the friction disc 21 to be moved laterally into engagement with the friction disc 19 and thereby be operatively connected with the sprocket wheel 15. The sleeve 23, see more particularly Figures 5 and 6, has keyed to it a bevel gear 40 which meshes with a bevel gear 41 which is fixed to a shaft 42 suitably journaled in the machine frame.

In order to vary the relative speed between the bevel gear 40 and the driven gear 41, we provide novel means whereby the gear 40 can be adjusted longitudinally on the sleeve 23. The hub of the gear 40 is extended to form an exteriorly threaded sleeve 43. 44 designates a cap nut in threaded engagement with the sleeve 43 and bearing against the thrust bearing of the journal bracket 18, and a lock nut 45 is provided which retains the parts in their adjusted position. If it is desired to drive the shaft 42 at a lower speed than that at which the gear 41 will drive it, the gear 41 is removed and another gear substituted for it. In order to remove this gear 41, the

shaft 42 has a reduced portion forming a shoulder 46, see Figure 5. Slidable on such reduced portion is a shouldered sleeve 47 which is keyed to the shaft 42 and the gear 41 is mounted on the sleeve 47 by means of a pin 48. When this pin 48 is removed and the sleeve 47 moved rearwardly, the gear 41 can be removed and another gear substituted for it.

The sleeve 47 is mounted in roller bearings 49 carried by a casing 50 which is journaled on the conical ends of the bearing bolts 51 which are carried by a swiveled yoke 52, see also Figure 3, mounted on the front end standards 1 of the machine frame.

The journal bolts 51 are secured in adjusted position by means of lock nuts 53. After a gear with a smaller number of teeth than the gear 41 has been substituted for the gear 41, the gear 40 is moved longitudinally into mesh with such substituted gear by loosening the lock nut 45 and then rotating the cap nut 44 in a direction to bring the teeth of the gear 40 into mesh with the teeth of the substituted gear. The lock nut 45 is then tightened and the parts are locked in their proper position for operating.

The gear 41 and the gear or gears which are substituted for it are cut in such a manner that the faces of their teeth are parallel with the faces of the teeth of the gear 40.

In accordance with our present invention, the machine is constructed in duplicate so that quills, cops, bobbins or spools can be wound at opposite sides of the machine, and for this reason the driving mechanism is constructed in such a manner that one or both sides of the machine can be operated at the same or different speeds.

As we have described in detail the driving mechanism for one side of the machine, we will describe the driving mechanism for the other side of the machine simply in sufficient detail to describe the cycle of the operation, it being understood that the driving mechanism driven by the sprocket wheel 15 for driving one side of the machine is the same as that for driving the other side of the machine.

The sprocket wheel 15 is provided with a friction face 54, see Figure 5, with which co-operates a friction disc 55 positioned between such friction face 54 and a friction disc 56 mounted similarly to the friction disc 21 and controlled by means of a yoke 57 which controls the operative engagement of a gear 58 with a gear 59. The gear 59 is carried by a shaft 60 which corresponds to the shaft 42. The shaft 42 has fixed to it in spaced relationship a desired number of friction driving wheels 61, see more particularly Figures 1, 3, 8 and 12 respectively.

The pinion 32, see more particularly Figure 2, meshes with a gear 62 which is

mounted on a shaft 63 journalled in the machine frame. The shaft 63 has mounted on it a cam 64 which bears against a roller 65, see Figure 3, said roller being carried by a lever 66 which carries a stud 67 having its shank extending through a slot 68 in a lever 69 and secured in adjusted position within said slot 68 by means of a nut 70, so that the levers 66 and 69 are pivotally connected. The lever 69 is fulcrumed at its lower end, as at 71, to a fixed portion of the machine frame. The lever 69 has a rocking movement. The lever 66 is fulcrumed on a shaft 72 which extends through the lever 69 and in order to provide for the proper relative movement between the levers 66 and 69, the lever 66 is provided with a laterally extending recess 73. The lever 66 has operatively connected to it one end of a lever 74, the opposite end of which is connected to a fixed portion of the machine frame, so that the tendency of this spring is to always maintain the roller 65 in contact with the cam face of the cam 64.

The upper end of the lever 69 is pivotally connected at 75 to a reciprocatory rod 76 which is guided in the guide bracket 77 carried by the rod 78 which form tracks for the carriage, which latter will be hereinafter fully described. The reciprocatory rod 76 is made in sections and juxtaposed ends are provided with oppositely directed threads which engage with a turnbuckle 79 or its equivalent, whereby the starting position of the carriage can be varied.

Referring now to Figure 2, the shaft 63 carries an eccentric 80 which co-operates with the straps 81 to effect the reciprocation of a pawl actuating rod 82 which at its upper end has fixed to it an arm 83, see more particularly Figure 6, said arm being pivotally mounted in the rod 82, as at 84. The arm 83 has pivotally connected to it one end of an arm 85, which latter has mounted on its upper end a pawl 86 which co-operates with a ratchet 87 mounted on a shaft 88, see also Figure 4.

The stroke of the pawl 86 is always the same, but, in order to vary its co-operation with the ratchet 87, we provide a semi-circular guard 89, the hub of which is loosely mounted on the shaft 88. This semi-circular guard has a portion of its outer face serrated, as at 90, and a spring pressed plunger 91 is provided which engages such serrations to hold the guard 89 in its adjusted position. It will thus be seen that the guard 89 can be rotatably adjusted to prevent the co-operation of the pawl 86 with the ratchet 87 during a desired portion of the operative stroke of such pawl 86. The ratchet 87 is prevented from moving in a reverse direction by means of a spring pressed pawl 92. The manner in

which the ratchet 87 is carried by the shaft 65 88 will best be understood by reference to Figure 4, from which it will be seen that the ratchet 87 is carried by a sleeve 93 which is keyed at 94 to the shaft 88. The shaft 88 is threaded at intervals, as indicated at 95.

The reciprocatory carriages and their adjuncts.

Any desired number of carriages are employed in accordance with the number of 75 quills, cops, bobbins or spools which are to be wound on the machine. 96 designates the carriages, the frames of which are provided with rollers 97, see Figure 12, which travel on the track forming rods 78, see more 80 particularly Figures 8, 9, 12 and 14.

The rod 76 passes through the frame of the first two carriages 96 and the carriages are secured in adjusted position on the rod 76 by means of the nuts 98, see for example, Figures 12 and 14. It will thus be seen that each carriage reciprocates in unison with the reciprocatory rod 76. Each carriage 96 is provided with a thread carrier 99 which is slidably mounted on the 90 superimposed cross rods 100 of the carriage frame, see more particularly Figures 8, 9, 12 and 14.

The yarn or thread carrier 99 has pivotally mounted in it at 101 one end of an 95 arm 102, which carries a feed nut 103 which is in the form of a half nut adapted to be brought into and out of engagement with the threaded portions 95 of the shaft 88 so as to cause the thread carrier 99 to travel 100 toward the right or in the direction of its operative stroke. The arm 102 has connected to its outer end a rod 104 which passes through the lever 105, and its lower end is provided with an adjustable stop 105 or abutment 106 for one end of a spring 107 carried by the lower end of said rod 104. The upper end of said spring bears against an abutment 108 carried by the lever 105. The rod 104 has adjustable on it a nut 109 110 which bears against the upper face of the lever 105. The lever 105 is pivotally mounted in the thread carrier 99 and 110, and its outer end or handle portion is weighted, as indicated at 111, in order to 115 form a counterbalance.

The lever 105 carries a pin 112 which is adapted to seat in the notch 113 of a weighted lever 114 which is pivoted at 115 in the thread carrier 99. This lever is weighted 120 at its lower end so that it will tend to move in the direction seen in Figure 8. 116 designates a lever which is fulcrumed on the cone shaped ends of the bearing pins 117 of the lever 105. 118 designates a lever which is 125 pivotally supported at 115 and provided with a pin 119 which overhangs the lever 116. The lever 118 is normally held in the

position seen in Figure 8 by the yarn or thread 120 which passes through the porcelain guide 121 over the porcelain rollers 122 and beneath the porcelains 123 carried by the lever 118. The frame of the carriage 96 has fixedly connected with it a threaded brake rod 124 which travels in unison with the carriage. The lever 105 is provided with a threaded portion 125, which, when the lever 105 is moved upwardly, meshes with the brake rod 124 to maintain the thread carrier 99 in fixed relation with respect to the carriage 96. 126 designates a bell crank lever pivotally carried at 127 on the thread carrier 99 see Figure 12. One end of this lever 126 forms a fingerpiece by means of which it can be readily operated, and its other end forms a hook 128 which bears against a pin 129 on the lever 105 on one side of its fulcrum, whereby, when the finger portion of the bell crank lever 126 is raised, the lever 105 will be rocked on its fulcrum in a direction to release it from its engagement with the brake rod 124.

The lever 105 is provided with a cam face 130 which is adapted to co-operate with the rod 131 carried by the levers 132 which are fulcrumed on a rod 133 suitably carried by the machine frame. The lower ends of these levers act as a counterbalance. One of the levers 132 is provided with an arm 134 which travels in the path of the inner track forming rod so as to limit the downward movement of one of the levers 132 and thereby of the rod 131. One of the levers 132 has pivotally connected to it, at 135, one end of a link 136 which has a pin and slot connection at 137 with a dog 138, which latter is pivotally supported at 139, on an arm 140 which is loosely mounted on a rod 141 carried by the machine frame. The arm 140 has an inclined face 220 with which the inclined face 221 of the dog 138 co-operates and the arm 140 is fixed to a lever 142 fulcrumed on the rod 141, and having a tail piece 143, which extends beneath the shaft 133 in order to limit the movement of the lever 142 in one direction. The opposite end of the lever 142, see also Figure 11, is inwardly deflected to form a hook 144, which is adapted to engage the shoulder 145 on the plunger 146, guided in the bracket 147, which is pivotally connected at 148 to the quill holder 149. A spring 150 is provided, which is interposed between the bracket 147 and the head 151 of the plunger 146, so that the tendency of the spring 150 is to maintain the plunger 146 in its raised position.

Each quill holder 149, see also Figure 16, is fulcrumed at 152 on the machine frame, so that, when the plunger 146 is drawn downwardly, the friction roller 153 on the quill spindle 154 will be moved into engagement

with its respective friction wheel 61, so that the proper rotation will be imparted to its quill spindle 154. The quill spindle is mounted within the quill holder 149 on a ball bearing 155 and an adjustable end thrust bearing 156 is carried by the quill holder 149 to take up the end thrust on the spindle. The quill spindle 154 is provided with the spring clips 157 to hold the quill or cop tube 158 in position on the quill spindle 154. The quill holder 149 has its hub 159 loosely mounted on the stud shaft 152 and a spring 160 is provided one end of which is fixed to the frame, as at 161, and the other end thereof is connected with the sleeve 159, so that the tendency of this spring 160 is to maintain the quill holder 149 in its inoperative or stationary position, as seen in Figure 14. The hub 159 of the quill holder 149 is provided with a projecting lug 162 which travels in the path of a rotatably adjustable stop member 163, which is secured in its adjusted position by means of a bolt 164, which passes through a slot 165 in the stop member 163. This stop member 163 is in the form of a split band which forms a shoulder 166 which serves as a stop or abutment for the lug 162.

167 designates a lever which is fulcrumed on one of the rods 78 and provided at its forward end with a fork 168 within which is received the pin 169 which is fixed to and extends laterally from a plunger 146. The lever 167 has secured to it one end of a spring 170, the free end of which bears against the tail piece 143 of the lever 142. The lever 167 has pivotally connected to it at 171 one end of a lever 172 which is provided with a weighted end 173. The lever 173 has pivotally connected to it at 174 a plunger 175 slidable in a plunger casing 176 which forms a part of the lever 167. The plunger 175 is provided with a shoulder 177 against which bears one end of a spring 178, the opposite end of which bears against the inner wall of a recess 179 in which the plunger is mounted, see Figure 15. The plunger 175 is interiorly threaded to receive a threaded rod 180 which carries a nut 181, which is adjustable to limit the stroke of the plunger 175 in one direction. The threaded rod 180 has secured to its upper end a member 182, which is recessed to receive a laterally extending rod 183, which is secured in position by means of a set screw 184. The rod 183 is of such length that it will contact with the under face of the lever 105 in any position which the thread carrier 99 may assume with respect to its carriage.

The hub of the friction wheel 61, see Figures 8 and 12, carries a lug 185 which at certain times is in the path of the tooth 186 of the dog 138.

187 designates swifts which are mounted

in brackets 188 supported on the rods 9 and 10, respectively. The skeins of yarn 189 are carried by the swifts 187 in the usual manner, and the yarn 120 passes from the swifts 187 to yarn guides 190 carried by a tension take-up bar 191 which is slid able on rollers 192 and has connected to it a cable 193, the free end of which is connected to a weight 194. The yarn, after passing 10 through the yarn guide 190 on the tension take-up member 191 passes through the por celains 195 and then through the yarn guides 121 over the rollers 122 and beneath the por celains 123 carried by the levers 118. The 15 yarn then passes through the yarn severing mechanism which will now be described.

The yarn severing mechanism.

The plate 196 of each carriage 99 forms 20 at its upper end a stationary knife blade 197 and has hinged to it, as at 198, a movable knife blade 199. One end of the knife blade 199 is provided with an offset shoulder 200, see Figure 13, adapted to engage a latch 201 on one end of a lever 202. The opposite end of this lever is bent to form an arm 203 carrying thereon a laterally extending cam arm 204. Mounted upon the upper one of the guide shafts 100 is an adjustable stop 30 member 205, against which the arm 203 contacts at the end of the travel of the carrier 99. A spring member 206, see Figures 9 and 14, is fixed upon the pins 207 and 198, and one end is engaged in the free end of 35 the lever 202 to normally keep the latch 201 in engagement with the shoulder of the movable blade 199. The opposite end of the spring 206 passes over the top of the blade member 199 and normally tends to press it 40 downwardly. The thread 120 passes between the fixed blade 197 and the movable blade 199, thence through por celains 208 and 209, and thence direct to the quill or 45 cop tube 158 to which it is connected in any desired manner.

In order to automatically reset the movable knife blade 199 when the carrier 99 is returned to its starting position on its carriage, the blade is provided with a laterally 50 extending arm 210, the forward face of which is beveled to form a cam face, as at 211, in order that when the thread carrier is returned to its initial or starting position, this bevel face 211 will engage a fixed cam 55 212 on the carriage 96 and cause the movable blade 199 to be raised into the position seen in Figure 13, at which time it inter locks with the latch 201, see also Figure 9.

In the ordinary operation of winding ma chines the quills, cops, bobbins or spools af 60 ter they are wound, are placed in a trough at the side of the machine. We have found it advantageous in practice to employ a con veyor to convey the quills, cops, bobbins or

spools, which have been completed, to a de spired point of utilization. 65

Quill conveyor.

For the sake of clearness of illustration, we have shown this construction in Figure 3 and have omitted it from other figures of the drawings. The gear 32, see Figure 5, or the corresponding gear 213, is intergeared by means of a gear 214 with a gear 215 mounted on a conveyor shaft 216 around which passes a conveyor apron 217 which it will be understood also passes around a shaft or roller (not shown) at the opposite end of the machine. The conveyor apron travels over suitable guide rollers 218. We preferably 75 employ a flat belt and in order to retain the quills, cops, bobbins or spools on the conveyor apron during its travel, we provide the side guide members 219 which are carried in any desired manner by the machine 80 frame and extend above the side edges of the conveyor apron. 85

It is sometimes desirable to remove one or more of the carriages and their adjuncts as a unit for the purpose of inspection or re pair and in order that this will not interfere with the operation of the machine, we preferably form the rod 76 in sections having juxtaposed ends, the sections being adapted to interlock, as will be understood 90 by reference to Figure 17 and the sections are connected together by means of a coupling collar 223, see Figure 17. In a similar manner the brake rod 124 is made in sections the juxtaposed ends of the sections being adapt ed to interlock and be connected together by means of a coupling collar 224. The rods 100 are made in sections and the juxtaposed ends of the sections are adapted to interlock and be secured in assembled position by means of coupling collars 225. The feed shaft 88 is also made in sections the juxtaposed ends of the sections being adapted to interlock and be retained in assembled position by means of a coupling 226. It will be 100 understood from Figure 17 that one or more of the carriages can be removed and the sections of the rods and shaft be connected together so that the entire machine will not be out of commission but all of the quill winding units remaining can be operated in 110 the same manner as before. 115

The operation.

The operation of our novel automatic winding machine will now be readily apparent to those skilled in the art to which this invention appertains and is as follows:— 120

The machine is preferably constructed in duplicate so that any desired number of quills can be wound at each side of the ma chine and if both sides of the machine are in 125 operation one operator ordinarily attends to one side of the machine and another opera

tor attends to the opposite side of the machine.

Assuming now that the motor 12 is in operation, the sprocket chain 14 will be continuously driven and thereby the combined sprocket and friction wheel 15. If the clutch levers 28 and 57 are in their inoperative position, the gear 15 will be revolving without imparting any drive to the machine.

Assuming now that the different swifts have been filled with skeins of silk or other type of yarn or thread and the yarn or thread 120 has been passed through its various guides, as already described, that the 15 quill or other tubes have been placed on the quill spindles 154, and the loose ends of the yarn connected to the quill tubes 158, the machine is ready for operation. The operator now presses down the spring pressed 20 plunger 34 thereby releasing the locking member 36 from its engagement with the shoulder 39 and the spring 30 causes the friction disc 21 to be moved into such position that it will be frictionally driven by 25 the friction disc 19 and the sprocket wheel 15. The sleeve 23 is connected to the hub of the friction disc 21 in such a manner that it revolves in unison with it and since this sleeve 23 carries the gear 40, the gear 40 will 30 be revolved and thereby the gear 41 which is fixed on the shaft 42.

As the shaft 42 revolves, the different friction wheels 61 will revolve in unison with it. The sleeve 22 carries the gear 32, 35 thereby through the gear 62 driving the shaft 63. The shaft 63 has mounted on it the cam 64 which effects the reciprocation of the lever 69 and the bar 76 connected with it, and, as this bar also has connected to it 40 the carriages 96, a reciprocatory movement is imparted to all of the carriages 96.

Assuming now that the thread carrier 99 of a carriage 96 is at its initial or starting position, which is at the left hand end of 45 the carriage, it will be understood that the thread carrier reciprocates in unison with the carriage and during such reciprocations of the carriage it is intermittently advanced step by step.

The parts are now in proper position to commence the winding operation. The operator moves the handle 172 from its inoperative position seen in full lines in Figure 12 into the position seen in dotted lines in Figure 8, the lever 172 then dropping back into the position seen in full lines in said Figure 8. As the lever 172 is raised from the position seen in full lines in Figure 12 into that seen in dotted lines in Figure 8, the lever 167 is rocked on its fulcrum 78, see Figures 8 and 12. The plunger 177 moves upwardly against the tension of the spring 178 and causes the rod 183 carried by the head 182 on the rod 180 to contact 60 with the handle portion of the lever 105,

thereby rocking said lever on its fulcrum 110. This movement of the lever 105 draws downwardly the rod 104, thereby bringing the feed nut 103 into engagement with the threads 95 on the shaft 88, so that the carriage 70 is now intergeared with the feed shaft 88. The feed shaft 88 is intermittently driven by a ratchet movement, which will now be described.

The pawl actuating rod 82 is reciprocated 75 by the eccentric 80, thereby imparting an oscillatory movement to the pawl 86 and the consequent intermittent rotation step by step of the ratchet 87 and of the shaft 88 which it drives. The amount of rotation imparted 80 to the shaft 88 can be varied, as before described, by adjustment of the guard 89, so that the pawl 86 will co-operate with the ratchet 87 during its entire operative stroke or during only a desired portion of such 85 stroke.

During the rocking movement of the lever 167 the forked end 168 co-operating with the pin 169 will cause the plunger 146 to be drawn downwardly, and, as the lever 167 90 rocks on its fulcrum, the spring 170 bearing against the tail piece 143 of the lever 142 will cause the hook shaped end 144 of such lever 142 to move inwardly so as to overhang the shoulder 145 on the plunger 146. 95

This downward movement of the plunger 146 causes the quill holder 149 to rock on its fulcrum 152 in a direction to bring its friction roller 153 into operative engagement with the friction wheel 61, so that the quill 100 spindle 154 on which the friction roller 153 is mounted will be continuously revolved at a speed which is relatively much greater than the speed of reciprocation of the carriage 96. The quill tube 158 is held in position on the spindle 154 by the spring clip 157 and revolves with the spindle, it being understood that the end of the yarn or thread has prior to this time after passing through its various guides, as shown in 110 Figures 8 and 12, been wound around or otherwise connected to the quill tube sufficiently to cause the winding of the yarn on the quill tube during the revolution of the latter. It will be understood that as the 115 lever 105 is rocked on its fulcrum as described, the pin 112 will seat in the notch 113 of the lever 114, thereby retaining the lever 105 in the position seen in Figure 8.

During the winding of the quill, cop, 120 bobbin or spool, the carriage reciprocates with the same length of stroke. It will be seen, however, that the yarn or thread 120 passes through the guide 121 on the thread carrier so that as the thread carrier is progressively advanced during the winding operation the yarn is properly positioned to form the desired formation of quill, cop, 125 bobbin or spool.

When the thread carrier 99 reaches the 130

end of its operative stroke, the quill is completed and at this time the yarn severing mechanism is operated.

Operation of the yarn severing mechanism.

As the thread carrier 99 reaches the end of its operative stroke, the lever 203 contacts with the adjustable fixed stop 205 thereby rocking the lever 202 on its fulcrum, releasing the latch 201 and the spring 206 causes the movable knife blade 199 to move downwardly to cut the yarn or thread 120. When the yarn or thread 120 is cut the lever 118 will normally drop. If, however, the yarn or thread should bunch up and hold the lever 118 in the position seen in Figure 8 or the knife fails to cut, the slight further advance of the carriage will cause the cam arm 204 to move inwardly the upper arms of the levers 116 and 114. This inward movement of the arm 114 causes the notch 113 to be moved out of the path of the pin 112 thereby permitting the weighted end 111 of the lever 105 to cause said lever to rock on its fulcrum 110. This causes the cam face 130 to co-operate with the rod 131 of the lever 132 thereby moving inwardly the link 136 due to the pin and slot connection 137 with the pawl 138 so that the tooth 186 is in the path of the lug 185 carried by the hub of the friction wheel 61. As the friction wheel 61 is continuously revolving, this lug 185 will contact with the tooth 186 and rock the pawl 138 on its fulcrum 189 and cause the inclined face 220 of such pawl 138 to engage with the inclined face 221 on the arm 140 which is connected with the lever 142. This causes the lever 142 to be rocked rearwardly to effect a release of the hook 144 from the shoulder 145 on the plunger 146 thereby permitting the spring 160 to rotate the quill support 149 in a direction to bring the friction wheel 153 out of engagement with the driving friction wheel 61 so that the quill spindle is no longer driven. The lever 142 has its upper arm of greater weight than its lower arm so that it assumes the position seen in Figure 11, the tail piece 143 being about to contact with the rod 133, see Figure 11.

As the lever 105 moves from the position seen in Figure 8 into that seen in Figure 12, it causes the rod 104 to be moved upwardly, thereby rocking the arm 102 on its fulcrum 101 and causing the feed nut 103 to become disengaged from the feed screw 88. The continued movement of the lever 105 causes the threaded portion 125 to engage with the threaded brake rod 124 so that the thread carrier 99 is retained in the position at which it was arrested.

Stop operation when yarn is severed.

If the yarn 120 accidentally breaks or is

severed the winding of the quill is automatically arrested and also the feed of the thread carrier 99 in order to give the operator an opportunity to connect the broken ends of the yarn and continue the winding of the quill.

As before explained, the yarn passing beneath the porcelains 123 retains the lever 118 in the position seen in Figure 8 and in dotted lines in Figure 12. Assuming now that the yarn should break the lever 118 drops downwardly from the position seen in dotted lines in Figure 12 into that seen in full lines in said figure.

As the lever 118 moves downwardly the pin 119 carried by said lever engages with the lever 116 to rock it on its fulcrum 117. This lever 116 carries a pin 222 which now contacts with the lever 114 releasing the notch 113 from its engagement with the pin 112 on the lever 105, thereby permitting the lever 105 to move from the position seen in Figure 8 to that seen in Figure 12. This movement of the lever 105 as before explained is operative to stop the rotation of the quill spindle, and it is also operative to stop the feed of the thread carrier 99 as before explained.

After the quill has been wound, as herein explained, the operator removes the quill with its tube and places it on the traveling conveyor 217 which conducts it to a desired point of utilization. The operator then places a new quill tube in position on the spindle 154 and threads the yarn through the guides and connects it with a new quill tube which has been placed on the quill spindle. The operator then returns the thread-carrier 99 to its initial or starting position by taking hold of the finger piece of the lever 126 to rock it on its fulcrum and thereby cause the hook 128 to bear against the pin 129 on the lever 105 to disengage such lever 105 from the brake rod 124, whereupon the thread carrier 99 can be moved back to its initial or starting position. This takes place against the action of the spring 107 so that as soon as the operator releases his pressure from the lever 126 the spring 107 raises the lever 105 into such position that it will reengage with the brake rod 124.

As the thread carrier 99 returns to its initial or starting position the cam face 211 on the arm 210 of the movable knife 199 cooperates with the stationary cam 212 to rock the movable knife 199 on its fulcrum from the position seen in Figure 14 into that seen in Figure 13, see also Figure 9, whereupon the latch 201 is engaged with the shoulder 200 of the movable knife 199. The lever 172 is now raised and released and the winding of the new quill now takes place in the manner hereinbefore described.

Special attention is directed to the manner in which the feed of the thread carrier 99 during the reciprocations of the carriage 96 can be adjusted, attention being directed more particularly to Figures 4 and 6. The operative stroke of the pawl 86 is always the same. The effective stroke of the pawl with respect to the ratchet 87 can, however, be varied by rotatably adjusting the guard 89 which is secured in its adjusted position by means of the spring actuated plunger 91.

The length of stroke of the carriage can be adjusted by adjusting the position of the stud 67 in the slot 68. If a finer adjustment is desired it can be obtained by rotating the turnbuckle 79 in the proper direction.

It is necessary in machines of this character to vary the length of stroke of the carriage in accordance with the character of the yarn or thread which is to be used.

It will be understood from the foregoing that the machine may be operating continuously as to given quills and yet not be operating as to a particular quill, the yarn or thread of which has been broken.

Each carriage and its adjuncts although driven in the same manner are independently controlled by the operator, so that any of the carriages or quill winding mechanism for a particular quill can be out of operation without affecting the operation of the winding mechanism of another quill.

It will be seen that the spindle 154 is made in sections so that a portion thereof is detachable whereby another spindle section can be substituted which will be adapted to receive a bobbin, spool or other structure adapted to receive a tube of any desired construction on which the thread is to be wound.

It will now be apparent that we have devised a novel and useful construction of an automatic winding machine which embodies the features of advantage enumerated as desirable in the statement of the invention and the above description, and while we have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described our invention, what we claim as new and desire to secure by Letters Patent, is:—

1. In a winding machine, the combination with spindles and means to actuate them, of a plurality of reciprocatory carriages, a thread carrier slidably mounted in each carriage and adapted to receive the yarn or thread, means to effect the step by step advance of a thread carrier during the recip-

rocation of its carriage, and automatically actuated brake mechanism to lock said head with respect to its carriage in case the yarn or thread breaks. 65

2. In a winding machine, the combination with the spindles and means to actuate them, of a plurality of reciprocatory carriages, a thread carrier slidably mounted in each carriage and adapted to carry the yarn or thread, means to effect the step by step advance of a head during the reciprocations 75 of its carriage, a brake rod fixed to each carriage, and means carried by said carrier and automatically operated in case the thread or yarn is severed to lock said head with respect to said brake rod. 80

3. In a winding machine, the combination with the spindles and means to actuate them, of a plurality of reciprocatory carriages, a thread carrier for each carriage, slidably mounted therein, and adapted to 85 carry the yarn or thread, a feed shaft, means to actuate it, a feed nut carried by a carrier to co-operate with said feed shaft, a lever mounted in each carrier and controlling its feed nut, and a brake member on said carriage and into engagement with which said lever is moved when its feed nut is disengaged from said feed shaft. 90

4. In a winding machine, the combination with the spindles, and means to actuate 95 them, of a plurality of reciprocatory carriages, a thread carrier for each carriage slidably mounted therein and adapted to carry the yarn or thread, a feed shaft, means to actuate it, a feed nut carried by a carrier to be engaged with and disengaged from said feed shaft, a lever mounted in each thread carrier to control its feed nut, and manually actuated means co-operating with 100 a lever to move its feed nut out of engagement with said feed shaft without arresting the rotation of said spindles. 105

5. In a winding machine, the combination with the spindles and driving means for said spindles, of a plurality of reciprocatory 110 carriages, there being a spindle for each carriage, a lever on each carriage controlling the driving means for its respective spindle, a carrier slidably mounted in each carriage and adapted to carry the yarn or 115 thread, means to intermittently feed a carrier during the reciprocations of its carriage, a second lever carried by said carrier and controlling said feeding means, and means actuated by said first lever to move 120 said second lever in a direction to render operative the feeding means for said carrier.

6. In a winding machine, the combination with the spindles and driving means for said spindles, of a plurality of reciprocatory 125 carriages, there being a spindle for each carriage, a lever on each carriage controlling the driving means for its respective spindle,

- a carrier slidably mounted in each carriage and adapted to carry the yarn or thread, means to intermittently feed a carrier during the reciprocations of its carriage, a second lever carried by said carrier and controlling said feeding means, a spring pressed plunger connected with said first lever, and a rod operatively connected with said plunger and co-operating with said second lever to move it in a direction to operatively connect said carrier with its feeding means.
7. In a winding machine, the combination with the spindles and driving means for said spindles, of a plurality of reciprocatory carriages, there being a spindle for each carriage, a lever on each carriage controlling the driving means for its respective spindle, a carrier slidably mounted in each carriage and adapted to carry the yarn or thread, means to intermittently feed a carrier during the reciprocations of its carriage, a second lever carried by said carrier and controlling said feeding means, a plunger connected with said first lever, a tension device for said plunger, a rod longitudinally adjustable with respect to said plunger, and means operatively connected to said rod to actuate said second lever in a direction to render operative the feeding means for said carrier.
8. In a winding machine, the combination with the spindles and driving means for said spindles, of a plurality of reciprocatory carriages, there being a spindle for each carriage, a lever on each carriage controlling the driving means for its respective spindle, a carrier slidably mounted in each carriage and adapted to carry the yarn or thread, means to intermittently feed a carrier during the reciprocations of its carriage, a second lever carried by said carrier and controlling said feeding means, a member connected with said first lever, a tension device for said member, means to vary the longitudinal length of said member, and means operatively connected with said member to move said second lever in a direction to render operative the feeding means for said carrier.
9. In a winding machine, the combination with the spindles and driving means for said spindles, of a plurality of reciprocatory carriages, there being a spindle for each carriage, a lever on each carriage controlling the driving means for its respective spindle, a carrier slidably mounted in each carriage and adapted to carry the yarn or thread, means to intermittently feed a carrier during the reciprocations of its carriage, a second lever carried by said carrier and controlling said feeding means, means actuated by said first lever to move said second lever in a direction to render operative the feeding means for said carrier, and a brake member with which said second lever interlocks when said feeding means is inoperative to feed said carrier.
10. In a winding machine, a reciprocatory carriage, a feed shaft, a feed nut co-operating with said shaft, a thread carrier by which said feed nut is carried, a lever on said carrier operatively connected with said feed nut to actuate it, a tension device for said lever, a pin on said lever, a second lever pivotally carried by said carrier and having means to engage said pin, and brake mechanism co-operating with said first lever and manually controlled by said second lever.
11. In a winding machine, a reciprocatory carriage, a feed shaft, a feed nut co-operating with said shaft, a thread carrier by which said feed nut is carried, a lever on said carrier operatively connected with said feed nut to actuate it, a tension device for said lever, a pin on said lever, a second lever pivotally carried by said carrier and having means to engage said pin, brake mechanism co-operating with said first lever and manually controlled by said second lever, and means set into operation by the severing of the yarn or thread to operate said first lever in a direction to effect the disengagement of said feed nut from its feed shaft.
12. In a winding machine, the combination with the spindles and means to actuate them, of reciprocatory carriages, a thread carrier for each carriage slidably mounted therein and adapted to carry the yarn or thread, a lever on said carrier having porcelains beneath which the yarn passes to normally maintain said lever in raised position, a second lever controlled by said first lever, a third lever controlled by said second lever and having a notch, a fourth lever having a pin to engage said notch and lock it in operative position, means controlled by said fourth lever to intermittently feed said carrier and a controlling device for the spindle actuated means automatically controlled by said fourth lever to arrest the movement of the spindle when the yarn or thread is severed.
13. In a winding machine, a spindle rotatably mounted and provided with a lug, a rotatably adjustable stop with which said lug co-operates, a tension device tending to move said lug toward said stop, a friction drive for said spindle, and means to automatically render the friction drive inoperative when the yarn or thread which is being wound on the spindle is severed.
14. In a winding machine, a support rotatably mounted, a spindle extending into said support, an antifriction bearing on which said spindle is mounted, a thrust bearing for said spindle, a tension device for said support, and means to rotate said spindle.
15. In a winding machine, a support rotatably mounted, a sectional spindle rotat-

- ably mounted in said support and having one section detachable, a friction member on said support, a friction wheel to co-operate with said friction member, a tension device tending to move said support in a direction to move the friction member away from said friction wheel, a plunger connected with said support, a lever operative to lock said plunger in position to retain the friction member and friction wheel in engagement, and means automatically actuated on the severing of the yarn or thread to actuate said lever to effect the release of said plunger. 10
- 15 16. In a winding machine, a support rotatably mounted, a sectional spindle rotatably mounted in said support and having one section detachable, a friction member on said support, a friction wheel to co-operate with said friction member, a tension device tending to move said support in a direction to move the friction member away from said friction wheel, a plunger connected with said support, a lever operative to lock said plunger in position to retain the friction member and friction wheel in engagement, means automatically actuated on the severing of the yarn or thread to actuate said lever to effect the release of said plunger, 20 and manually controlled means to reset said lever and to move said plunger into position to be locked. 25
- 30 17. In a winding machine, a support rotatably mounted, a spindle in said support, a plunger connected with said support, a spring tending to rotate said support, a friction member on said spindle, a friction wheel, means to drive said friction wheel, a lever having one end adapted to engage said plunger to retain said friction member and friction wheel in engagement, an arm carried by said lever, a pawl mounted on said arm, a link having a pin and slot connection with said pawl, a second lever to which said link is connected, a third lever operatively connected to said plunger to move it, a reciprocatory carriage, a thread carrier slidably mounted therein, means to intermittently feed said thread carrier a fourth lever controlling such feed and adapted to control said third lever, and means controlled by the severing of the yarn or thread to automatically actuate said fourth lever and thereby stop said spindle. 45
- 50 55 18. In a winding machine, a support a spindle therein, a friction drive for said spindle, a plunger connected with said support, a lever having one end adapted to engage said plunger to lock it in position to render the friction drive operative, a pawl carried by said lever adapted to be set in position to be actuated by said friction drive to release said lever from said plunger and render the friction drive inoperative to drive the spindle, a reciprocatory carriage, 60
- 65 a thread carrier slidably mounted thereon and carrying the yarn or thread, means to intermittently feed said carrier, and means automatically controlled by the severing of the yarn to render said carrier feeding 70 means inoperative and to move said pawl into a position to be actuated by the friction drive of the spindle. 75
19. In a winding machine, the combination with the spindles and means to actuate them, of reciprocatory carriages, a thread carrier for each carriage slidably mounted therein and adapted to receive the yarn or thread, means to intermittently feed said carrier during the reciprocations of its carriage, a lever to render said feed operative or inoperative, and yarn severing mechanism including a latch having a cam arm to automatically actuate said lever to render the carrier feeding means inoperative 80 when the winding operation is completed. 85
20. In a winding machine, the combination with the spindle and means to actuate them, of reciprocatory carriages, a thread carrier for each carriage slidably mounted therein and adapted to receive the yarn or thread, means to intermittently feed a carrier during the reciprocations of its carriage, a lever to render said feed operative or inoperative, yarn severing mechanism including a latch having a cam arm to automatically actuate said lever to render the carrier feeding means inoperative 90 when the winding operation is completed, and a stop 95 in the path of said cam arm to positively actuate said latch if for any reason it should fail to be released. 100
21. In a winding machine, the combination with the spindles and means to actuate them, of reciprocatory carriages, a thread carrier for each carriage slidably mounted therein and adapted to carry the yarn or thread, means to intermittently advance said carrier during the reciprocation of its carriage, means to automatically stop the feed of said carrier and render the spindle actuating means inoperative when the yarn or thread is cut, cutting mechanism having means to also stop the feed of said carrier 105 and render said spindle actuating means inoperative when the cutting mechanism is operated, and means to automatically reset said cutting mechanism after an article has been wound and said carrier has been returned to its starting position. 110
22. In a winding machine, the combination with the spindles and means to actuate them, of reciprocatory carriages, a thread carrier for each carriage slidably mounted 115 therein and adapted to carry the yarn or thread, means to intermittently advance said carrier during the reciprocations of its carriage, means to automatically stop the feed of said carrier and render the spindle ac- 120
- 125 130

- tuating means inoperative when the yarn or thread is cut, cutting mechanism including a movable knife blade having an arm provided with a cam face, a stationary cam in the path 5 of said cam face when the carrier is returned to its starting position, and means to release said carrier from its feeding means to permit the operator to return it to its starting position.
- 10 23. In a winding machine, the combination with a frame, of spindles mounted on opposite sides of the frame, a series of reciprocatory carriages mounted on opposite sides of the frame, a thread carrier for each carriage slidably mounted therein and adapted 15 to carry the yarn or thread, means to intermittently advance each carrier during the reciprocations of its carriage, and means to drive the spindles at one side of the machine 20 at a different speed of revolution from that of the spindles at the opposite side of the machine, thereby adapting the machine to wind at the same time yarn or thread of different characteristics.
- 25 24. In a winding machine, the combination with a frame, of spindles mounted on opposite sides of the frame, a series of reciprocatory carriages mounted on opposite sides of the frame, a thread carrier for each 30 carriage slidably mounted therein and adapted to carry the yarn or thread, means to intermittently advance each carrier during the reciprocations of its carriage, means to drive the spindles at one side of the machine at a 35 different speed of revolution from that of the spindles at the opposite side of the machine, and means to adjust the carrier feeding mechanism to cause the carriers at one side of the machine to advance at a different rate of 40 speed from that of the carriers on the opposite side of the machine, thereby adapting the machine to wind at the same time yarn or thread of different characteristics.
25. In a winding machine, the combination 45 with a frame, of spindles mounted on opposite sides of the frame, a series of reciprocatory carriages mounted on opposite sides of the frame, a thread carrier for each carriage slidably mounted therein and adapted 50 to carry the yarn or thread, means to in-

termittently advance each carrier during the reciprocations of its carriage, a driven member having friction faces on opposite sides thereof, a friction clutch for each friction face, and means controlled by each friction clutch to drive the spindles controlled there-by at each side of the machine.

26. In a winding machine, a driving gear having a threaded sleeve, a cap nut on said sleeve to longitudinally adjust it, a lock nut to lock the sleeve with respect to the cap nut, a driven gear meshing with said driving gear, a shaft on which said driven gear is mounted, and means to longitudinally adjust said shaft whereby the driven gear can be removed and a gear with a lesser number of teeth secured to said shaft.

27. In a winding machine, a driven sleeve, a gear keyed thereto and provided with a threaded sleeve, a cap nut engaging said threaded sleeve and bearing against said first sleeve, a lock nut on said threaded sleeve, a driven gear meshing with said first gear, a sleeve on which said driven gear is mounted, means to secure said driven gear and its sleeve to said shaft, and means to longitudinally adjust said shaft when it is desired to replace said driven gear.

28. In a winding machine, the combination with the spindles and means to actuate them, of reciprocatory carriages, a thread carrier for each carriage slidably mounted therein and adapted to receive the yarn or thread, means to intermittently feed a carrier during the reciprocations of its carriage, a lever to render said feed operative or inoperative, yarn severing mechanism including a latch having a cam arm to automatically actuate said lever to render the carrier feeding means inoperative when the winding operation is completed, and a stop in the path of said cam arm to positively actuate said latch if for any reason it should fail to be released and to stop the spindles.
